(57) **CLAIM**

We claim the ornamental design of a chair arm, as shown and described.

DESCRIPTION

FIG. 1 is a right, front perspective view of a right-side version of a chair arm embodying our new design. A left-side version of the chair arm, which also embodies the design, is a mirror image thereof.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The dashed line shown on the arm pad is understood to represent stitching.
